UNITED STATES PATENT OFFICE.

NEWELL P. COWELL, OF CLEVELAND, OHIO, ASSIGNOR TO THE COWELL PLATFORM AND COUPLING COMPANY, OF SAME PLACE.

CAR-COUPLING.

SPECIFICATION forming part of Letters Patent No. 278,403, dated May 29, 1883.

Application filed January 28, 1882. (Model.)

To all whom it may concern:

Be it known that I, NEWELL P. COWELL, of Cleveland, in the county of Cuyahoga and State of Ohio, have invented certain new and useful Improvements in Car-Couplers; and I do hereby declare the following to be a full, clear, and exact description of the invention, such as will enable others skilled in the art to which it pertains to make and use the same.

10 My invention relates to car-couplers, and more particularly to that class known as "automatic car-couplers," that are adapted to engage with the opposite couplers when the same are brought together without the interposition 15 of any mechanical device or endangering the life or limbs of a brakeman; and it consists in parts and combination of parts, as will more fully hereinafter be described and claimed.

In the accompanying drawings, Figure 1 represents an isometric view of the under portions 20 of two opposite car-platforms carrying my improved couplers, one of the couplers being shown in closed and the other in open adjustment. Fig. 2 is a view showing the couplers locked together. Fig. 3 is a horizontal sectional view through one draw-bar and coupler, showing the mechanism for locking the coupler in open and closed adjustment; and Fig. 4 is a similar view, showing the stop drawn out 25 and disengaged from the pivoted coupling-head.

In the drawings, A A' represent the platforms, preferably of passenger-coaches.

B B' represent the draw-bars, which consist 35 preferably of two metal plates sufficiently removed to permit the introduction of the spring and stop; also, the pivoted head or coupler C, which is also adapted to turn upon the pivot D. The pivoted head shown in Fig. 3 is provided 40 with the angular portion c, which is adapted to engage with the same angular portion of the opposing coupler. It is also provided with another angular face upon its opposite side, as shown at c', which is adapted to bear against 45 the stop E when the coupler is open, as shown in Fig. 1. The pivoted head has shoulders or projections on its side, which slide upon the circular portion of the plates composing the draw-bars. Thus the pivoted head is adapted 50 to revolve backward until the shoulders strike the non-circular portion of the draw-bar.

E is a stop adapted to prevent the pivoted head C from turning forward farther than shown at C' in Fig. 1 by the angular portion c' coming in contact with the stop, as there 55 shown. When the coupler is closed the stop rests against the back portion, d, of the pivoted head, as shown in Fig. 3, and prevents its turning forward until the stop is removed. A coil-spring, H, or its equivalent, is used to 60 retract the stop when drawn out and released. On one side of the stop E is a rod, e, that is attached to the plates composing the draw-head. This keeps the stop E in place as it moves backward and forward. It also prevents the stop E from being drawn out too far by a projection on the stop E coming in contact with the rod e.

In the drawings I have illustrated one method of operating the stop E. It consists in connecting the stop, by means of a chain, F, with a lever, G, the lever being pivoted in the platform of the car and adapted to be operated from the upper side of the platform.

Having described the construction of my improved coupler, I will briefly describe its operation. When the pivoted hooks of the couplers of two cars to be coupled together are in their closed position, as illustrated in Fig. 3, the curved faces of the hooks will strike each other as the cars come together, causing the hooks to recede laterally until they have passed by a sufficient distance to allow their faces c to engage each other, as illustrated in Fig. 2; or should the hooks be in their open position, 85 they will pass each other, and after the cars have come to a standstill, they can be turned and locked in their closed position, as shown in Fig. 2. When it is desired to release the couplers the lever G is operated, and the stop 90 E thereby withdrawn, thus allowing the hook to turn on its pivot and disengage the couplers of two adjacent cars. This operation can be done as readily when the cars are on a curve as when on a straight line of track.

To adapt cars provided with my improved couplers to be coupled to cars having the ordinary link-coupler, I attach to the pivot D a hook, D', with which may be engaged the ordinary link, and in this manner the cars may be coupled, 100 though furnished with different forms of couplers. To prevent the links from displacement

or becoming disengaged from the hook D', a spring and suitable locking mechanism may be provided.

What I claim is—

- 5 1. The combination, with a draw-bar, of a coupling-head pivoted to the end thereof and provided with an angular face, c, and with the straight faces d and e², and the spring-actuated stop interposed between the draw-bar and coupling-head, and adapted to operate substantially as described.
- 10 2. The combination, with the draw-head B and coupling-head C, pivoted in the head of the draw-head, of the sliding stop E, located

in a recess formed between the coupler and draw-head, said stop being constructed with a forwardly-projecting arm at its lower end and a rearwardly-projecting arm at its upper end, and a spring located between a seat on the draw-head and the rearwardly-projecting arm of the sliding stop, substantially as set forth.

In testimony whereof I have signed my name to this specification in the presence of two subscribing witnesses.

NEWELL P. COWELL.
